FIG. 1 is a front perspective view of an artificial tree trunk showing my new design;

FIG. 2 is a top plan view of the artificial tree trunk of FIG. 1; FIG. 3 is a bottom plan view of the artificial tree trunk of FIG. 1;

FIG. 4 is a front elevation view of the artificial tree trunk of FIG. 1;

FIG. 5 is a right-side elevation view of the artificial tree trunk of FIG. 1;

FIG. 6 is a rear elevation view of the artificial tree trunk of FIG. 1;

FIG. 7 is a left-side elevation view of the artificial tree trunk of FIG. 1; and,

FIG. 8 is another perspective view of the artificial tree trunk of FIG. 1.

The broken lines shown in FIG. 1 depict environment and form no part of the claimed design.
